CLAIM

The ornamental design for a power cord, as shown and described.

DESCRIPTION

FIG. 1 is a perspective view of a power cord showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines form no part of the claimed design and represent the boundary line between the claimed design and unclaimed portions.

The power cord is shown with symbolic breaks in its length and the appearance of any portion of the power cord between the pairs of break lines forms no part of the claimed design.

1 Claim, 4 Drawing Sheets
